UNITED STATES PATENT OFFICE

CHARLES T. BRADY, OF DETROIT, MICHIGAN

MAGNIFYING AND ILLUMINATING DEVICE

Application filed May 31, 1927. Serial No. 195,569.

The present invention pertains to a novel magnifying and illuminating device designed for use in the examination of parts of the body and also serviceable in connection with documents, finger prints and the like.

The principle object of the invention is to provide a device of this character which will stand on a floor and permit of universal adjustment as to height and direction. The main support which stands on the floor is telescopic and carries a flexible tubing which in turn supports a universally mounted lamp socket.

The socket is formed with a shield adapted to cover the lamp and further to reflect light therefrom towards the object under examination. The shield has a pair of lens holders pivoted thereto, and one or both of these holders may be brought into the line of vision from the observer's eye to the object under examination.

The device comprises still another lens holder adjustably attached to the support and spaced from the shield. This holder is normally beneath the lamp and may be brought into alignment with the above mentioned holders to modify the magnifying effect.

The invention is fully disclosed in the following description and in the accompanying drawings, in which—

Figure 1 is an elevation of the device;

Fig. 2 is a detail plan view thereof;

Fig. 3 is a plan view of the auxiliary lens

support;

Fig. 4 is a detail longitudinal section thereof; and

Fig. 5 is a detail longitudinal section of the supporting pedestal.

Reference to these views will now be made by use of like characters which are employed to designate corresponding parts throughout.

The main support for the device consists of a vertical tubular pedestal 1 standing on a base 2. A post 3 is slidably mounted in the pedestal and is surrounded by a collar 4 resting on the upper end of the pedestal as shown in Figure 5. This upper end is threaded as at 6 for receiving a cap 7 penetrated by the post and internally threaded at 8 to cooperate

with the threads 6. An expandable body 9, such as rubber, surrounds the post 3 between the collar 4 and the top of the cap 7 and may be expanded radially by turning the cap downwardly on the pedestal, thereby becoming clamped around the post and holding the same in a fixed position.

The upper end of the post 3 is provided with a fitting 10 to which is attached one end of a flexible tubing 11 having a socket head 12 at its other end. This head receives a ball 13 to which is fixed a handle member 14 formed with a lamp socket 15 carrying a shield and reflector 16 as disclosed in my co-pending application Serial No. 195,573, filed May 31, 1927. The edge of the member 16 is formed with a pair of spaced ears 17 adjacent which is formed a curved stop 18. This construction accommodates a pair of lens holders 19 each having a lug 20 received between the ears and held in this position by a clamp screw 21 passing through the ears and lugs.

To the lower end of the tub 11 is fitted a clamp 22 having a bracket 23 pivoted thereto. To the bracket is attached a socket member 24 by means of a clamp screw 25 lying at right angles to the pivotal connection 22 between the members 22 and 23. The socket receives a tube 26 which in turn receives a rod 27 having a split and expanded inner end 28 as shown in Figure 4. The outer end of the rod is bifurcated as at 29 for supporting another lens holder 30 adapted to be secured therein by a clamp screw 31.

A conductor 32 is passed into the fitting 10 through the tubing 11 and handle 14 to a lamp 33 inserted in the socket 15. The flow of current to the lamp is controlled by a screw switch 34 mounted on the lamp socket.

By means of the flexible tubing 11 and the universal coupling 12-13 between the tube and the lamp assembly the lamp may be directed towards the object under examination, with the lens holders and reflector 16 between the object and the eye of the observer. The holder 30 is brought into the line of sight by manipulation of the telescopic parts 26 and 27 and adjustment at the pivots 22 and 25. Due to the pivotal mounting of the holders 19,

either one or both of the magnifying lenses supported thereby may be placed in the line of vision, and the holder 30 may be swung entirely out of the line of sight if desired.

5 Although a specific embodiment of the invention has been illustrated and described, it will be understood that various alterations in the details of construction may be made without departing from the scope of the invention as indicated by the appending claims.

10 What I claim is:—

15 1. A magnifying and illuminating device comprising a support, a lamp socket having a universal connection therewith, a shield carried by said socket, a pair of lens holders pivoted to said shield, and another lens holder adjustably attached to said support and adapted for alignment with the first named holders.

20 2. A magnifying and illuminating device comprising an extensible support, a lamp socket having a universal connection therewith, a shield carried by said socket, a pair of lens holders pivoted to said shield, and another lens holder adjustably attached to said support and adapted for alignment with the first named holders.

In testimony whereof I affix my signature.
CHARLES T. BRADY.
